DESIGN FOR A SKIRT OR THE LIKE

Henry J. Perahia, Brooklyn, N. Y.

Application August 24, 1934, Serial No. 53,047

Term of patent 3½ years

To all whom it may concern:

Be it known that I, HENRY J. PERAHIA, a citizen of the United States, residing at Brooklyn, Kings County, State of New York, have invented a new, original, and ornamental Design for a Skirt or the like, of which the following is a specification, reference being had to the accompanying drawing, forming a part thereof, in which Fig. 1 is a front view of a skirt showing my new design, and Fig. 2 is a rear view thereof.

I claim:

The ornamental design for a skirt or the like, substantially as shown.

In testimony whereof, I have signed this application.

HENRY J. PERAHIA.
